UNITED STATES PATENT OFFICE.

FOREST V. DETWILER, OF CHICAGO, ILLINOIS.

REFRIGERATOR.

1,099,284.

Specification of Letters Patent.

Patented June 9, 1914.

Application filed June 21, 1909. Serial No. 503,372.

To all whom it may concern:

Be it known that I, FOREST V. DETWILER, a citizen of the United States, residing at Chicago, in the county of Cook and State 5 of Illinois, have invented certain new and useful Improvements in Refrigerators, of which the following is a specification.

This invention relates to improvements in refrigerators and has for one of its objects to provide improved means whereby either the city supply of water or ice may be used as a cooling medium.

A further object is to provide an improved cooling casing within which is arranged the food or provision receptacle and which cooling casing may be readily and bodily removed from the outer casing.

A further object is to provide an improved air circulation apparatus.

20 A further object is to provide an improved up-going air circulation tube and improved means for removably supporting and securing the tube in position.

25 A further object is to provide an improved construction of food compartment or receptacle and improved means for supporting the receptacle and spacing the same from the walls of the cooling casing.

30 A further object is to provide an improved water cooling casing having down-going air circulation tubes within the walls thereof and improved means for protecting the inlet ends of the down-going air circulation tubes.

35 A further object is to provide improved means whereby the up-going air will be discharged from the food compartment and through the bottom of the ice and water tank.

40 A further object is to provide improved means for controlling the height of the water in the cooling casing, and improved means for discharging the water from the casing at will.

To the attainment of these ends and the 45 accomplishment of other new and useful objects, as will appear, the invention consists in the features of novelty in the construction, combination and arrangement of the several parts hereinafter more fully described and claimed and shown in the accompanying drawings illustrating an embodiment of the invention, and in which—

50 Figure 1 is a longitudinal sectional view of an improved refrigerator of this character constructed in accordance with the principles of this invention and taken on line

1—1 of Fig. 4. Fig. 2 is a sectional view taken on line 2—2 of Fig. 3. Fig. 3 is a sectional view taken on line 3—3 of Fig. 2. Fig. 4 is a sectional view taken on line 4—4 of Fig. 3. Fig. 5 is a detail perspective view, partly in section and partly broken away, of the water cooler or casing. Fig. 6 is an enlarged detail sectional view on line 6—6 of Fig. 2. Fig. 7 is a detail sectional view on line 7—7 of Fig. 6. Fig. 8 is a perspective view of the up-going air circulation tube. Fig. 9 is a detail perspective view of the supporting rack for the cooling casing and the food compartment. Fig. 10 is a perspective view of the food receptacle.

Referring more particularly to the drawings and in the present exemplification of the invention, the numeral 15 designates the 75 outside casing of the refrigerator which may be of any desired size and configuration but in the present exemplification of the invention the casing is shown as being rectangular in cross section. The casing is 80 provided with an open front and a removable closure 16 is provided for closing the open side and this closure 16 is provided with one or more door openings which are adapted to be closed by suitable doors or 85 closures 17 so that when it is desired to have access to the ice compartment or food receptacle, the respective door or closure 17 may be opened and when it is desired to remove the food chamber and the cooling casing from the outer casing 15, the closure 16 90 may be opened to permit such removal. Suitable fastening devices 18 may be provided for the closure 16 and the ordinary fastening devices 19 may be provided for 95 the closures 17.

Arranged within the outer casing is a cooling casing having hollow walls and this cooling casing preferably comprises an open tank having a bottom 20 and peripheral 100 walls 21. The tank thus formed may be of any desired size and configuration but is preferably of a size to substantially fill the outer casing and to conform to the contour thereof and the peripheral walls or flanges 21 105 may be of any desired height according to the width of pan or tank desired. The tank preferably forms the top of the cooling casing and is provided with apertures or openings 22 extending through the bottom thereof 110 adjacent opposite walls of the tank and these openings extend for substantially the entire

length of the bottom in close proximity to and parallel with the adjacent wall or flange 21. Hollow walls comprising spaced members 23 and a bottom 24 are provided and these walls are of a width substantially equal to the width of the apertures or openings 22 and of substantially the same length as the apertures. The tops of the hollow walls thus formed are open and the extremities of the sides 23 at the top are deflected laterally as at 25 to form overhanging flanges or lips, so that when the body portions of the walls are inserted through the apertures or openings 22 in the bottom of the tank, the overhanging lips or flanges 25 will engage the bottom adjacent the apertures or openings for supporting the walls in position. If desired, any suitable fastening means, such as solder or the like, may be provided for securing the walls and the tank together to prevent displacement of one with respect to the other and to form fluid tight joints. The bottom 20 of the tank is also provided with an aperture or opening 26 preferably adjacent the back thereof and is located between the apertures or openings 22, and supported by and secured to the bottom 20 is a tubular member 27 which communicates with the aperture or opening 26, as shown more clearly in Figs. 3 and 5. This tubular member 27 is of any desired height and is provided for a purpose to be hereinafter set forth.

Arranged within the hollow walls of the cooling casing are downgoing air circulation tubes 28, any number of which may be provided and these tubes 28 are preferably of an external diameter somewhat less than the internal width of the hollow walls so that when the tubes 28 are placed in position a cooling fluid or water space will be formed in the walls of the casing around the tubes 28. These tubes are supported and secured in position in any desired or suitable manner and rest upon the bottom 24 of the respective walls so as to communicate with apertures 29 in the bottom. The upper ends 30 of these tubes project for any desired distance above the bottom 20 of the tank and preferably extend a short distance above the top edge of the surrounding walls or flanges of the tank.

The upper extremities of the walls or flanges 21 adjacent the hollow walls of the casing are bent upon themselves as at 31 (see Fig. 5) and the extremities of these bent portions are again bent backwardly as at 32 to form upwardly opening supports. Secured to the bottom 20 of the tank and adjacent each of the flanges 25 of the wall members 23 and extending substantially the entire length of the tank adjacent the edges of these flanges are clips or members 33, which are provided with an offset portion 34

projecting away from the flange 25 and these offset portions 34 are spaced from the bottom 20 of the tank.

In order to protect the upper extremities of the downgoing air circulation tubes, suitable caps or shields are provided and comprise a body portion 35 having one edge 36 bent downwardly to form a flange adapted to engage in the upwardly opening support or clip 32. A portion of the body of the shields or caps 35 is bent as at 37 at substantially right angles to the remaining portion thereof and the edge of the portion 37 is deflected laterally as at 38. The extremity of this laterally deflected portion 38 is bent back upon the said portion as at 39 to form a rearwardly opening clip which is adapted to engage over the offset portion 34 of the respective members 33 so that when the caps or shields are in position they will not only protect the upper extremities of the down-going air circulation tubes but will also serve as a means for bracing and securing the walls of the water casing in position. The caps or shields are provided with a plurality of apertures or openings 40 through which the extremities 30 of the air tubes 28 project and if desired suitable protecting caps 40, which may be constructed of any desired or suitable reticulated material, are provided which extend over the ends of the tubes 28 to prevent the entrance therein of any foreign matter.

The portion 37 of the shields or caps may be provided with apertures or openings 41 adapted to be covered by reticulated material, such as wire gauze or the like, and these openings serve as passages through which the water in the tank may discharge into the hollow walls of the water casing. Arranged also within each of the hollow walls of the cooling casing is a tubular member 43 (see Fig. 6) one extremity of which is secured to the bottom 24 of the hollow walls to communicate with an aperture or opening 44 in the bottom and this tubular member 43 is provided with one or more apertures or openings 45 adjacent the bottom 24 of the hollow walls, which serve as outlets for the water in the walls to be discharged through the opening 44 in the bottom of the walls. Any suitable means may be provided for controlling these openings 44. A suitable and efficient means comprises a rotary valve 46 which is provided with apertures or openings 47 adapted to be brought into register with the openings 45 in the member 43 or to be moved out of register. Any suitable means may be provided for controlling this valve 46. A suitable and efficient means for accomplishing this end comprises a valve stem 48 which preferably extends upwardly and beyond the top of the tubular member 43 and into the tank or pan sup-

ported by the walls, and an operating handle 49 is secured to the extremity of the stem 48 preferably beyond the cap or shield 35. A suitable guide or bracket 50 may be 5 provided, if desired, for supporting and guiding the stem 48. This tubular member 43 also serves as an overflow pipe through which the water discharges from the tank. The valve 46 for controlling the openings 10 45 is hollow, as shown more clearly in Fig. 7, so as not to obstruct the flow of the water which enters the tubular member directly from the tank and in order to control and regulate the height of the water in the tank 15 so as to cause the water to accumulate in the hollow walls, any suitable means may be provided. A suitable and efficient means for accomplishing this end comprises a tubular section 51 and has communication 20 with the tubular member. By adjusting the section 51 with respect to the member 43 it will be apparent that the water will accumulate in the tank to a height until it overflows the edge of the adjustable section 25 51, so that the water will enter the tubular member 43 to be discharged through the opening 44. The cooling casing thus formed is adapted to be removably held within the outer casing 15. Arranged with- 30 in the casing 15 and secured to the bottom thereof is a drip pan 52 and leading from the drip pan is a discharge pipe 54.

In order to support the cooling casing above the bottom of the drip pan 52, a suitable supporting frame is provided, which 35 may be of any desired or suitable construction but is preferably constructed of metal and comprises spaced side frames 55 which are connected together in any desired or 40 suitable manner, preferably by means of a cross bar or member 56 at the rear and a cross bar or member 56' at the front. These frames 55 are provided with open 45 tops 57 and open sides 58 and a shield or partition 59 is supported by each of the frames 55 to form an obstruction for the direct passage of air through the frames from the top to the bottom and also as a means for deflecting the air currents which 50 enter the frame 55 through the open tops 57 and discharge the same through the open sides 58. The frames 55 are also provided with laterally projecting flanges or supports 60 which are preferably arranged in the 55 same plane as the plane of the partitions 59 for a purpose to be set forth. The support thus formed is placed within the casing 15 so as to rest upon the bottom of the drip pan 52 and the cooling casing is then placed 60 in position so that one of the hollow walls thereof will rest upon each of the frames 55 so that the openings 29 in the bottoms 24 of the walls will stand above the openings 57 in the supporting frames 55 so that the 65 down-going air currents passing through

the tubes 28 will pass through the openings 57 in the frames and be deflected by the partitions 59 through the sides 58.

The cooling casing is of a height to terminate some distance short of the top of the outer casing 15 to form a cooling fluid supply chamber. Supported by the partitions 59 of the frames 55 are tubular members 61 which are secured in position in any desired or suitable manner and these tubular members register with openings 62 in the partition 59. One of these tubular members 61 is provided for each of the overflow pipes or tubes 43 and stands in close proximity to the discharge end thereof to cause the tubes to 70 register and communicate with the tubular members 61 so that when water is discharged through the openings 44, it will enter the tubular members 61 and be discharged into the drip pan, thereby obviating the danger 75 of the water striking and splashing against the partitions 59.

Arranged within the tank supported by the hollow walls of the cooling casing is a support 63 which is preferably constructed 90 of perforated metal. The edges 64 of this support are deflected downwardly, as shown more clearly in Fig. 5, and the extremity thereof is deflected laterally as at 65 to form a supporting foot, which latter is adapted to engage and rest upon the laterally deflected portion 38 of the caps or shields 35, whereby the support will be held in position and spaced from the bottom 20 of the tank. This support 63 is of any desired size and configuration but is preferably of a size and configuration to fit and substantially fill the space between the portions 37 of the caps or shields 35 and the front wall of the tubular member 37 and the front of the outer 95 casing. An ice rack 66 is provided which rests upon the support 63 and upon which the ice rests.

Arranged within the ice compartment 67 is a partition 68 which is spaced from the rear wall of the casing 15. The ends 69 of the partition 68 are bent rearwardly, as shown more clearly in Fig. 2, and the extremities 70 of the ends 69 are deflected laterally so as to engage the inner face of the 110 rear wall of the outer casing to space the partition 68 therefrom, and suitable fastening devices 71 may be provided for removably securing the partition in position. The partition is of a height to terminate 115 short of the top of the casing to permit its ready insertion and removal and may be provided with suitable apertures or openings 72 adjacent the top edge thereof, which may be protected by reticulated material 73, such as wire gauze or the like, and through which the up-going air currents may be discharged into the ice chamber 67.

The food receptacle is preferably sectional in construction and is constructed of any 130

desired or suitable material, such as porcelain or the like, and comprises a bottom section 74. This section is provided with a rear upwardly projecting wall 75 and side walls 76, and the corners formed between the bottom 74 and the walls 75, 76, are rounded as shown at 77, to permit the bottom to be readily cleaned and to obviate the danger of the accumulation of dirt or sediment in the corners between the bottom and walls. Supported by the bottom section is a back wall 78 having forwardly projecting extremities 79, which latter form portions of the side walls. The back wall 78 is adapted to rest upon the edge of the upwardly extending portion 75 of the bottom section, and the forwardly extended portions 79 are adapted to engage and rest upon portions of the edges of the upwardly extending sides 76 of the bottom section. The side walls 80 of the food receptacle are adapted to rest upon the remaining portions of the edges of the portions 76 of the bottom with their rear edges abutting the front edges of the forwardly extending portions 79 of the back 78. The upper section of the food receptacle comprises a top 81 having a downwardly projecting portion 82 at its rear edge adapted to engage and rest upon the top edge of the back section 78. The top is also provided with downwardly projecting portions 83 at the sides thereof which are adapted to engage and rest upon the upper edges of the side sections 80 and also upon the upper edges of the forwardly projecting portions 79 of the rear wall. The corners formed between the various walls are all rounded as at 77 and any suitable fastening means, such as cement or the like, may be provided for securing the sections against displacement. If desired, additional fastening means, such as dowel pins 84 or the like, may be provided which extend into adjacent edges of the sections.

The top 81 of the food receptacle is provided with a slot or elongated aperture 85, which is arranged to communicate with the opening 26 in the bottom 20 of the tank and extends substantially across the top of the food compartment. An up-going air circulation tube or flue 86 is provided which is of a configuration to conform to the aperture or opening 85 and to extend through the opening. The lower edges of the tubular member 86 are cut and bent to form spaced series of laterally projecting ears or flanges 87, 88, extending beyond the sides thereof and laterally projecting ears or extensions 89 extend beyond the ends of the tubular member. This tubular member 86 is preferably angular in cross section and extends through the top of the cooling casing and is of an external size somewhat less than the internal size of the tubular member 27 through which latter it projects.

When the food receptacle is placed in position and before the partition 68 is placed in the ice compartment, the ears or flanges 88 of the up-going air circulation tube 86 and the flanges 89 are bent laterally and into position. The tube or flue is then placed in position by extending the lower extremity thereof into and through the opening 85 in the top of the food receptacle until the flanges or ears 88, 89 rest upon the upper face of the top 81. When in this position the flanges 87 may be then deflected from the inside of the food receptacle and against the lower face of the top 81 so as to securely hold the flue or tube 86 against accidental displacement. The flue or tube 86 being of a size somewhat less than the internal size of the tubular member 27 will form a dead air space 90 between the two tubular members, thereby preventing the warm up-going air currents from coming directly in contact with a chilled surface to obviate the danger of the formation of water of condensation which would drip back into the food compartment. The space thus formed is closed as at 91 at the top of the tubular member 27 by means of a flange supported by and secured to the tube 86.

In order to brace the members 23 of the hollow walls to prevent collapsing or damage caused by the pressure or weight of the water, braces 92 may be provided which are arranged within the walls and preferably extend beyond the walls. Suitable fastening devices 93, such as nuts or the like, are provided for securing the supports in position adjacent the outer walls of the casing. The inner extremities of the braces 92 are formed into clips 94 and members 95, such as wood strips or the like, are provided and supported by these clips and these members 95 are provided with air circulation openings 96 therethrough. Any suitable number of these members may be provided throughout the height of the walls of the casing and the members serve as means for holding the sections of the food receptacle in position and for spacing the walls of the food receptacle from the walls of the cooling casing.

In use and when the ice is placed within the ice compartment 67 the drip water will flow from the tank into the hollow walls and also around the tubular member 27. When the walls and tank have been filled with water to a predetermined level, which level may be regulated by the adjustable sections 51 of the overflow pipes 43, any further supply of water will flow out of the pipes or tubes 43 to be discharged into the drip pan 52. At the same time the warm air currents in the food receptacle will rise and will be discharged through the bottom 20 of the tank into the space between the partition 68 and the rear wall of the casing within which space the up-going air circulation tube or

flue 86 is located. From this space the air will be discharged into the ice compartment 67 through the openings 72 and some of the air currents will pass over the top of the compartment, which latter terminates short of the top of the outer casing. When the temperature of the air thus discharged into the ice compartment is lowered, the air currents will enter the down-going air circulation tubes 28 to be discharged through the bottom of the hollow walls and against the partition 59. The partition will deflect the air currents through apertures or openings 97 in the walls of the food receptacle and the currents will rise in the compartment to again enter the tube 68. The side walls of the food receptacle may also be provided with additional apertures or openings 98 through which the cold air from the adjacent walls of the cooling casing will be discharged into the food compartment.

Any number of shelves 99 may be provided to form the food supports and these shelves are provided with apertures or openings 100 through which the air currents circulate. Any suitable means may be provided for removably supporting the shelves in position and for this purpose brackets 101 may be provided and these brackets may be secured in position and against the inner face of the walls of the food receptacle by means of suitable fastening devices 102 such as screws, nails, bolts or the like, which pass through the brackets, the walls of the food receptacle and into the members 95. Although the specific means of fastening and supporting the shelves is shown and described, it is to be understood that the shelves may be supported in any other manner, so as to permit the food receptacle to be removed from the water cooler or casing without having to first remove the supporting brackets for the shelves from the walls of the receptacle.

When the food receptacle is placed within the cooling casing it will be held in position and supported by means of the supporting frame and the bottom of the receptacle will engage and rest upon the projecting ledges 50 or supports 60 upon the frames 55 and will also rest upon the cross or connecting bars 56 between the frames.

When it is desired to use the city supply of water as a cooling medium instead of the ice, a pipe 103 is provided and which pipe is itself provided with any number of discharge nozzles 104. The pipe 103 is located in any desired or suitable position within the tank and is preferably supported adjacent to the rear thereof and to extend across the top. A supply pipe connection 105 is connected to the pipe 103 and extends through one of the walls of the outer casing, preferably the rear wall. A controlling valve 106 is also provided in the connection 105.

When the water supply is used as the cooling medium, the pipe 105 is connected to a suitable source of supply and the valve 106 opened so that the water will flow into the pipe 103 and be discharged through the nozzles 104 into the tank and from there will flow into the hollow walls of the cooling casing, in the same manner as the drip water. This pipe 103 is supported in any desired manner and may be provided and inserted when the refrigerator is constructed.

While in the present exemplification of the invention the supply pipe is shown as extending through the rear wall of the outer casing, it is to be understood that the pipe 20 may be arranged in any manner and may extend through any of the walls of the casing. With this improved construction it will be apparent that all of the parts may be readily removed from the casing and by 35 providing this improved form of food receptacle it will also be apparent that the formation of square corners between the walls is obviated, thereby rendering it possible to readily wash or clean the food receptacle.

In order to prevent accidental displacement of the cooling casing within the outer casing 15 during shipment or transportation, suitable fastening devices may be provided which preferably comprise blocks 15^a constructed of any desired or suitable material and these blocks may be removably secured to the inner walls of the outer casing in any desired or suitable manner, preferably by means of fastening devices 15^b such as screws or the like. Any number of these blocks may be provided and are arranged so as to engage and rest upon the upper edges of the walls of the tank. When it is 105 desired to remove the cooling casing from the outer casing, the cooling casing may be slid through the front of the outer casing without removing the blocks 15^a or the blocks may be first removed before the casing is removed.

In order that the invention might be fully understood, the details of the foregoing embodiment thereof have been thus specifically described but

What is claimed as new is—

1. In a refrigerator the combination of an inclosing casing, a cooling casing provided with hollow walls and having a source of supply of cooling fluid, down-going air circulation tubes within the walls of the cooling casing, and an up-going air circulation tube independent of the side walls of the cooling casing and extending from the inside of the cooling casing through the top 125 wall thereof.

2. In a refrigerator, the combination of an inclosing casing, a cooling casing having hollow walls and having a source of supply of cooling fluid, a down-going air circula- 130

tion tube within the walls, one end of the tube extending above the cooling casing, the other end of the tube discharging below the cooling casing, and an up-going air circulation tube independent of the walls of the cooling casing and leading from the inside of the cooling casing and discharging directly through the top thereof.

5. In a refrigerator, the combination of
10 an inclosing casing a removable cooling casing having a top and hollow side walls and having a source of supply of cooling fluid, a down-going air circulation tube within each of the walls, and an up-going air circulation
15 passage independent of the walls and leading directly through the top of the cooling casing from the interior thereof and between the hollow walls of the casing, said passage discharging above the top of the
20 cooling casing.

4. In a refrigerator, the combination of an inclosing casing, a removable cooling casing therein, said cooling casing having a top and hollow side walls, and having a
25 source of supply of cooling fluid, down-going air circulation tubes within the walls, an up-going air circulation tube separate from the cooling casing walls leading from the interior directly through the top of the cooling casing and projecting beyond the top, and means forming an inclosed air space around the up-going air circulation tube.

5. In a refrigerator, the combination of an inclosing casing, a removable cooling casing therein, said cooling casing having a top and hollow side walls and having a source of supply of cooling fluid, down-going air circulation tubes within the walls, an up-going air circulation tube separate from the
30 cooling casing walls extending directly through the top of the cooling casing and projecting beyond the top, and a tubular member surrounding and spaced from the up-going air circulation tube to form an inclosed air space around said air tube.

- 45 6. In a refrigerator, the combination of an inclosing casing, a removable cooling casing therein, said cooling casing being provided with a top and hollow side walls and having a source of supply of cooling fluid, down-going air circulation tubes within the walls, the top of the casing being provided with an aperture or opening therethrough, a tubular member supported by the top and surrounding the opening, and an up-going air circulation tube separate from the casing walls extending through the said tubular member and the opening, said air tube being of a size smaller than
50 the size of the said tubular member to form an air space therebetween.

- 60 7. In a refrigerator, the combination of an inclosing casing, a removable cooling casing therein, said cooling casing being provided

with a top and hollow side walls, and having a source of supply of cooling fluid, down-going air circulation tubes within the walls, the top of the cooling casing being provided with an aperture or opening therethrough, a tubular member separate from the cooling casing walls supported by the top and surrounding the opening and an up-going air circulation tube also separate from the cooling casing walls extending through the said tubular member and the opening, said air tube being of a size smaller than the size of the said tubular member to form an air space therebetween and extending for some distance beyond the inlet ends of the down-going air circulation tubes.

8. In a refrigerator, the combination of an inclosing casing, a cooling casing having an open front and back and provided with a top and hollow side walls, said casing having a source of supply of cooling fluid, down-going air circulation passages within the walls, and an up-going air circulation passage independent of the walls and discharging directly through the top of the cooling casing from the interior thereof and between the hollow side walls and above the top of the cooling casing.

9. In a refrigerator, the combination of an inclosing casing, a cooling casing having an open front and back and provided with a top and hollow side walls, said casing having a source of supply of cooling fluid, down-going air circulation passages within the walls, said top being provided with an opening therethrough extending substantially across the casing between the side walls, and a removable up-going air circulation tube separate from the casing walls extending through said opening.

40 10. In a refrigerator, the combination of an inclosing casing, a cooling casing having an open front and back and provided with a top and hollow side walls, said casing having a source of supply of cooling fluid, down-going air circulation passages within the walls, said top being provided with an opening therethrough extending substantially across the casing between the side walls, a tubular member supported by the top and surrounding the opening, and a removable up-going air circulation tube extending through the opening and tubular member and being spaced from the latter.

11. In a refrigerator, the combination of an inclosing casing and a removable cooling casing therein, said cooling casing having hollow walls, a tank supported by and having communication with the walls, said tank having a source of supply of cooling fluid, down-going air circulation tubes within the walls, and an up-going air circulation passage leading from the inside of the cooling casing and discharging directly through the

bottom of the tank at a point spaced from the walls of the inclosing casing and above the top of the cooling casing.

12. In a refrigerator, the combination of 5 an inclosing casing and a removable cooling casing therein, said cooling casing having hollow side walls, a tank supported by and having communication with the walls, said tank having a source of supply of cooling 10 fluid, down-going air circulation tubes within the walls, an up-going air circulation passage leading from the inside of the cooling casing and discharging directly through the bottom of the tank, and means separate 15 from the casing walls forming an inclosed dead air space around the said up-going air circulation passage.

13. In a refrigerator, the combination of 20 an inclosing casing and a removable cooling casing therein, said cooling casing having hollow walls, a tank supported by the walls and having communication with the space in the walls, said tank having a source of supply of cooling fluid, down-going air circulation tubes within the walls, and a removable up-going air circulation tube passing directly through the bottom of the tank and extending beyond the bottom of the 25 tank.

14. In a refrigerator, the combination of 30 an inclosing casing and a removable cooling casing therein, said cooling casing having hollow walls, a tank supported by the walls and having communication with the space 35 in the walls, said tank having a source of supply of cooling fluid, down-going air circulation tubes within the walls, the bottom of the tank being provided with an opening therethrough, a wall surrounding the opening separate from the casing walls, and an up-going air circulation tube extending through the opening and spaced from the surrounding wall.

15. In a refrigerator, the combination of 45 an inclosing casing, a removable cooling casing therein, said cooling casing comprising hollow side walls, a tank supported by the walls and having communication with the space in the walls, said tank forming the 50 top of the cooling casing and having a source of supply of cooling fluid, down-going air circulation tubes within the walls of the cooling casing, an up-going air circulation passage separate from the walls of the casing discharging directly through the 55 tank and above the bottom thereof, to form a straight passage for the air therethrough, and an overflow for the cooling casing.

16. In a refrigerator, the combination of 60 an inclosing casing, a removable cooling casing therein, said cooling casing comprising hollow side walls, independent of each other, a tank supported by the walls and having communication with the space in 65 the walls, said tank forming the top of

the cooling casing and having a source of supply of cooling fluid, down-going air circulation tubes within the walls of the cooling casing, an up-going air circulation passage discharging directly through the tank, an independent overflow for each of the hollow walls, and means for adjusting each of said overflows.

17. In a refrigerator, the combination of 75 an inclosing casing, a removable cooling casing therein, said cooling casing comprising hollow side walls, independent of each other, a tank supported by the walls and having communication with the space in the walls, said tank forming the top of the cooling 80 casing and having a source of supply of cooling fluid, down-going air circulation tubes within the walls of the cooling casing, an up-going air circulation passage discharging directly through the tank, and an 85 overflow pipe for each of the walls of the casing, each of said overflows being provided with an adjustable section for varying the height of the cooling fluid in the 90 casing.

18. In a refrigerator, the combination of 95 an inclosing casing, a removable cooling casing therein, said cooling casing comprising hollow side walls, a tank supported by the walls and having communication with 100 the space in the walls, said tank forming the top of the cooling casing and having a source of supply of cooling fluid, down-going air circulation tubes within the walls of the cooling casing, an up-going air circulation 105 passage separate from the walls of the casing discharging directly through the tank and above the bottom thereof, the inlet of the passage being disposed in close proximity to the bottom of the tank, and a 110 combined overflow and drain pipe for the casing.

19. In a refrigerator, the combination of 115 an inclosing casing, a removable cooling casing therein, said cooling casing comprising hollow side walls, a tank supported by the walls and having communication with the space in the walls, said tank forming the top of the cooling casing and having a source of supply of cooling fluid, down-going air circulation tubes within the walls of the cooling casing, an up-going air circulation 120 passage separate from the walls of the casing discharging directly through the tank, above the bottom thereof and with the 125 inlet in close proximity to the bottom of the tank, an overflow pipe for the cooling casing, said pipe being provided with a drain outlet adjacent the bottom of the casing for discharging the water from the casing, and means for controlling the said drain outlet at will.

20. In a refrigerator, the combination of 130 an inclosing casing, a removable cooling casing therein, said cooling casing comprising

- ing hollow side walls, a tank supported by the walls and having communication with the space in the walls, said tank forming the top of the cooling casing and having a 5 source of supply of cooling fluid, an overflow pipe for the cooling casing, said pipe being provided with a drain outlet adjacent the bottom of the casing for discharging the water from the casing, a rotary valve 10 for controlling the drain outlet, and a stem for operating the valve, and means adjacent the top of the cooling casing for operating the stem.
21. In a refrigerator, the combination of 15 an inclosing casing, a removable cooling casing therein, said cooling casing being provided with hollow walls and having a source of supply of cooling fluid, an overflow pipe for the cooling casing, said pipe having a 20 drain opening through its wall, a hollow valve within the pipe for controlling the drain opening whereby the overflow will pass through the valve when the drain opening is closed, and means for operating the 25 valve.
22. In a refrigerator, the combination of 30 an inclosing casing, a removable cooling casing therein, said cooling casing being provided with hollow walls and having a source of supply of cooling fluid, an overflow pipe for the cooling casing, said pipe having a drain opening through its wall, a hollow valve within the pipe for controlling the drain opening whereby the overflow 35 will pass through the valve when the drain opening is closed, means for operating the valve, and an adjustable section for the pipe whereby the height of the cooling fluid in the casing may be varied.
- 40 23. In a refrigerator, the combination of an inclosing casing, a removable cooling casing therein, provided with hollow walls and having a source of supply of cooling fluid, a removable food receptacle in the 45 cooling casing, down-going air circulation tubes within the walls of the cooling casing and a removable up-going air circulation tube separate from the walls and having communication with the interior of the food 50 receptacle directly through the top thereof, said tube projecting above the top of the cooling casing.
24. In a refrigerator, the combination of 55 an inclosing casing, a removable cooling casing therein provided with hollow walls and having a source of supply of cooling fluid, a removable food receptacle in the cooling casing, down-going air circulation tubes in the walls of the cooling casing and 60 an up-going air circulation tube removably secured to the food receptacle, said tube having communication with the interior of the food receptacle and projecting through the top of the cooling casing.
- 65 25. In a refrigerator, the combination of 70 an inclosing casing, a removable cooling casing therein, said cooling casing being provided with hollow walls, a tank supported by the walls and having communication with the space in the walls, said tank 75 having a source of supply of cooling fluid, a removable food receptacle within the cooling casing, down-going air circulation tubes within the walls of the cooling casing, and an up-going air circulation tube removably secured to and having communication with the food receptacle, said up-going air tube extending directly through and projecting beyond the bottom of the tank.
26. In a refrigerator, the combination of 80 an inclosing casing, a removable cooling casing therein, said cooling casing being provided with hollow walls, a tank supported by the walls and having communication with the space in the walls, said tank 85 having a source of supply of cooling fluid, a removable food receptacle within the cooling casing, down-going air circulation tubes within the walls of the cooling casing, an up-going air circulation tube removably secured to and having communication with the food receptacle, said up-going air tube 90 extending directly through and projecting beyond the bottom of the tank, and a tube supported by the bottom of the tank and 95 communicating with the opening therein and surrounding the air tube and being spaced from said air tube.
27. In a refrigerator, the combination of 100 an inclosing casing, a removable cooling casing therein, said cooling casing being provided with hollow walls, a tank supported by the walls and having communication with the space in the walls, said tank 105 having a source of supply of cooling fluid, a removable food receptacle within the cooling casing, down-going air circulation tubes within the walls of the cooling casing, said food receptacle having an opening in one wall, an up-going air circulation tube, said 110 tube extending through the tank with one end projecting into the opening in the wall of the food receptacle, and means on the tube engaging opposite faces of the wall of the food receptacle for removably securing the tube in position.
28. In a refrigerator, the combination of 115 an inclosing casing, a removable cooling casing therein, said cooling casing being provided with hollow walls, a tank supported by the walls and having communication with the space in the walls, said tank 120 having a source of supply of cooling fluid, a removable food receptacle within the cooling casing, down-going air circulation tubes within the walls of the cooling casing, said food receptacle having an opening in one wall, and an up-going air circulation tube, said tube extending through the tank, the 125 extremity of the tube projecting into the 130

opening in the wall of the food receptacle and portions of the tube being flanged against opposite faces of the wall of the food receptacle for removably securing the tube in position.

29. In a refrigerator, the combination of an inclosing casing, a removable cooling casing therein, said cooling casing being provided with hollow walls, a tank supported by the walls and having communication with the space in the walls, said tank having a source of supply of cooling fluid, a removable food receptacle within the cooling casing, down-going air circulation tubes within the walls of the cooling casing, said food receptacle having an opening in one wall, an up-going air circulation tube, said tube extending through the tank, the extremity of the tube projecting into the opening in the wall of the food receptacle and portions of the tube being flanged against opposite faces of the wall of the food receptacle for removably securing the tube in position, and means for forming an inclosed air space around the portion of the air tube within the tank.

30. In a refrigerator, the combination of an inclosing casing, a removable cooling casing therein, said cooling casing being provided with hollow walls, a tank supported by the walls and having communication with the space in the walls, said tank having a source of supply of cooling fluid, a removable food receptacle within the cooling casing, down-going air circulation tubes within the walls of the cooling casing, said food receptacle having an opening in one wall, and said tank being provided with an opening through its bottom, an up-going air circulation tube extending through the opening in the tank bottom with one extremity extending into the opening in the wall of the food receptacle, portions of the tube being flanged against opposite faces of the top wall of the receptacle for removably securing and supporting the tube, said tube being of a smaller size than the size of the opening in the bottom of the tank, and a tubular member surrounding the air tube and supported by the bottom of the tank, said member communicating with and being of an internal size substantially equal to the opening in the tank bottom.

31. In a refrigerator, the combination of an inclosing casing, a removable cooling casing therein, said cooling casing being provided with hollow walls and having a source of supply of cooling fluid, the top of the cooling casing terminating short of the top of the outer casing to form a fluid supply chamber, down-going air circulation tubes within the walls of the cooling casing and having communication with the fluid supply chamber, a partition in the said chamber and spaced from one wall thereof to form

an air passage having communication with the chamber, and an up-going air circulation tube separate from the casing walls leading from the interior of the cooling casing and directly through the top of said casing, 70 said tube discharging into the first said passage.

32. In a refrigerator, the combination of an inclosing casing, a removable cooling casing therein, said cooling casing being provided with hollow walls and having a source of supply of cooling fluid, the top of the cooling casing terminating short of the top of the outer casing to form a fluid supply chamber, down-going air circulation tubes within the walls of the cooling casing and having communication with the fluid supply chamber, a partition removably supported in said chamber and spaced from the wall thereof to form a passage communicating with the chamber, an up-going air circulation tube separate from the casing walls communicating with the interior of the cooling casing, said tube extending directly through the top of the cooling casing and 90 into and terminating in the said passage to discharge thereinto.

33. In a refrigerator, the combination of an outer casing, a removable cooling casing therein, said cooling casing comprising hollow walls, a tank supported by the walls and having communication with the space in the walls, said tank having a source of supply of cooling fluid, said cooling casing terminating short of the top of the outer casing 95 to form a fluid supply chamber, a partition within the chamber and spaced from one wall to form an air passage communicating with the chamber, down-going air circulation tubes within the walls of the cooling casing on one side of the partition and having communication with the chamber, and an up-going air circulation tube separate from the casing walls communicating with the interior of the cooling casing and extending directly through the bottom of the tank on the other side of the partition and discharging into the said passage.

34. In a refrigerator, the combination of an outer casing, a removable cooling casing 115 therein, said cooling casing comprising hollow walls, a tank supported by the walls and having communication with the space in the walls, said tank having a source of supply of cooling fluid, said cooling casing terminating short of the top of the outer casing to form a fluid supply chamber, a partition within the chamber and spaced from one wall to form an air passage communicating with the chamber, down-going air circulation tubes within the walls of the cooling casing on one side of the partition and having communication with the chamber, and a removable up-going air circulation tube separate from the walls communicating with 120

125 130

the interior of the cooling casing and extending directly through the bottom of the tank on the other side of the partition and discharging into the said passage.

35. In a refrigerator, the combination of an outer casing, a removable cooling casing therein, said cooling casing comprising hollow walls, a tank supported by the walls and having communication with the space in the walls, said tank having a source of supply of cooling fluid, said cooling casing terminating short of the top of the outer casing to form a fluid supply chamber, a partition within the chamber and spaced from one wall to form an air passage communicating with the chamber, down-going air circulation tubes within the walls of the cooling casing on one side of the partition and having communication with the chamber, an up-going air circulation tube communicating with the interior of the cooling casing and extending directly through the bottom of the tank on the other side of the partition and discharging into the said passage, and means 20 surrounding the up-going air tube and spaced therefrom to form an inclosed air space around the portion of the tube passing through the tank.

36. In a refrigerator, the combination of an outer casing, a removable cooling casing therein, said cooling casing comprising hollow walls, a tank supported by the walls and having communication with the space in the walls, said tank having a source of supply of cooling fluid, said cooling casing terminating short of the top of the outer casing to form a fluid supply chamber, a partition within the chamber and spaced from one wall to form an air passage communicating with the chamber, down-going air circulation tubes within the walls of the cooling casing on one side of the partition and having communication with the chamber, an up-going air circulation tube communicating with the interior of the cooling casing and extending directly through the bottom of the tank on the other side of the partition and discharging into the said passage, and a tubular member within the tank and supported by the bottom thereof, said member surrounding and being spaced from the up-going air circulation tube to form an inclosed air space there-around.

37. In a refrigerator, the combination of a cooling casing provided with hollow walls and having a source of supply of cooling fluid, a support for the casing, a removable food receptacle, means on the support for sustaining the food receptacle and for holding the bottom thereof below the bottom of the hollow casing, said receptacle having an opening in its wall below the bottom of the hollow casing, down-going air circulation tubes within the walls of the cooling casing and discharging below the casing, a parti-

tion supported by the said support for directing the air from said tubes into the food receptacle through the opening in the wall thereof, an overflow for the casing, and means for conducting the water from the 70 overflow through the said partition.

38. In a refrigerator, the combination of a cooling casing provided with hollow walls, and having a source of supply of cooling fluid, a support for the casing, a removable food receptacle, means on the support for sustaining the food receptacle and for holding the bottom thereof below the bottom of the hollow casing, said receptacle having an opening in its wall below the bottom of the hollow casing, down-going air circulation tubes within the walls of the cooling casing and discharging below the casing, a partition supported by the said support for directing the air from said tubes into the food receptacle through the opening in the wall thereof, said partition being spaced from the base of the cooling casing, and provided with an opening therethrough, an overflow pipe within the walls of the casing and terminating above the partition on the support and in line with the opening in the partition, and a tubular member supported by the partition and surrounding the opening therethrough, said tubular member registering with the overflow pipe.

39. In a refrigerator, the combination of a cooling casing having hollow walls and provided with a source of supply of cooling fluid, a removable food receptacle in the casing and having an opening in the wall thereof, means for supporting the receptacle with its bottom below the bottom of the casing, down-going air circulation tubes within the walls of the cooling casing, a partition arranged below and spaced from the ends of the tubes for deflecting the air into the food receptacle through the opening in the wall, an overflow pipe for the casing discharging through the bottom thereof, said partition having an opening therethrough and a tubular member surrounding the opening and forming a continuation of the overflow pipe.

40. In a refrigerator, the combination of a cooling casing provided with hollow walls and having a source of supply of cooling fluid, a removable non-metallic food receptacle in the casing, said receptacle having an opening in one wall and an up-going air circulation tube removably secured to the wall of the receptacle and having communication with the interior thereof through said opening.

41. In a refrigerator, the combination of a cooling casing provided with hollow walls and having a source of supply of cooling fluid, a removable non-metallic food receptacle in the casing, said receptacle having an opening in one wall and an up-going air 130

circulation tube, one end of the tube extending into the opening, and portions of the tube being flanged against the faces of the wall for removably securing the tube in position.

42. A refrigerator including in combination a cooling casing provided with hollow walls and having a source of supply of cooling fluid, a removable food receptacle in the casing, down-going air passages within the walls of the casing and an up-going air circulation tube, the inlet of which has communication with the food receptacle only, said tube projecting through the top of the casing and discharging therebeyond.

43. A refrigerator including in combination a cooling casing provided with hollow walls and having a source of supply of cooling fluid, a removable food receptacle in the casing, down-going air passages within the walls of the casing and an up-going air circulation tube supported by the receptacle, the inlet of said tube having communication with the food receptacle only, said tube projecting through the top of the cooling casing and discharging therebeyond.

44. A refrigerator including in combination a cooling casing provided with hollow walls, and a tank supported by the walls and having communication with the space in the walls, said tank forming the top of the

casing and having a source of supply of cooling fluid, a removable food receptacle in the casing, down-going air circulation passages within the walls of the casing, an up-going air circulation tube, the inlet of which has communication with the food receptacle only, said tube projecting through the tank and discharging therebeyond, and means forming a dead air space around the tube where it passes through the tank.

45. A refrigerator including in combination a cooling casing, said cooling casing having hollow walls, a tank supported by the walls and having communication with the space in the walls, said tank having a source of supply of cooling fluid, down-going air circulation tubes within the walls of the casing, an up-going air circulation tube extending through the tank, and means inclosing the portion of the tube which extends through the tank, and spaced therefrom to form an inclosed air space around the said portion of the air tube.

In testimony whereof I have signed my name to this specification, in the presence of two subscribing witnesses, on this 10th day of June A. D. 1909.

FOREST V. DETWILER.
